 Geoffrey E. Dobbin(57) **CLAIM**

The ornamental design for an eyepiece with reticle, as shown and described.

DESCRIPTION

FIG. 1 is a front view of the reticle of FIG. 2 shown isolated at a larger scale for clarity of disclosure; and, FIG. 2 is a front view of the viewing surface of an eyepiece with reticle.

The outer circular dashed-line perimeter around the reticle in FIG. 2 represents the viewing surface of an eyepiece to which the reticle is applied, and forms no part of the claimed design. The remaining dotted and dashed lines form part of the reticle and are included in the claimed design.
